UNITED STATES PATENT OFFICE

2,142,156

ELECTRIC SWITCH

Robert F. Sambleson, Bridgeport, Conn., assignor
to General Electric Company, a corporation of
New York

Original application November 15, 1935, Serial No.
49,931. Divided and this application January
15, 1938, Serial No. 185,175

12 Claims. (Cl. 200—152)

This application is a division of my copending application, Serial No. 49,931, filed Nov. 15, 1935, which is assigned to the same assignee as the present application.

5 The present invention relates to electric switches of the type having liquid contact circuit-closers for controlling the flow of current.

The object of my invention is to provide an improved construction and arrangement in a 10 switch of this type.

10 In the accompanying drawing, Fig. 1 is a sectional side elevation of a switch embodying my invention; Fig. 2 is a sectional view taken on line 2—2 of Fig. 1; and Fig. 3 is a diagrammatic view showing the construction and operation of 15 the liquid contact circuit closer.

Referring to the drawing, I have illustrated 20 my invention using a liquid contact circuit closer having a pair of cup-shaped metal terminals 1 which are separated by an insulating diaphragm 2 of refractory material, such as a ceramic material. The edges of the terminals are sealed by a bead 3 of glass which also seals the junctions between the diaphragm and the terminals. With 25 the space enclosed by the terminals is a suitable quantity of mercury 4 which forms the conduction medium between the terminals. In the manufacture of the circuit closer, the space enclosed by the terminals is evacuated and filled 30 with hydrogen at a pressure of one or more atmospheres which increases the current interrupting capacity of the circuit closer. As shown by the full lines in Fig. 3, the diaphragm 2 is provided with an opening 5 which is submerged 35 in the mercury when the circuit closer is in the current conducting position. When the circuit closer is in the current interrupting position, shown in dotted lines in Fig. 3, the opening 5 is above the mercury, and the circuit between the terminals is therefore broken or interrupted by 40 the insulating diaphragm 2. Due to the construction of the circuit closer, the interruption of the circuit between the terminals takes place in the mercury as the circuit closer is turned so 45 that the opening 5 in the diaphragm approaches the dotted line position. The above described construction is illustrative of a type of liquid contact circuit closer which is suitable for use in a switch embodying my invention.

50 For operating the liquid contact circuit closer, I have provided a handle 6 of molded thermoplastic material having forked ends 7 which envelope more than half the periphery of the circuit closer. One of the forked ends 7 is provided with projections 8 on opposite sides which

fit within recesses 9 in the terminals of the circuit closer and on opposite sides thereof and prevent relative rotation between the handle and the circuit closer. The forked ends of the handle are snapped in place while hot and are held in place by the resilience of the forked ends. The gripping of the handle is increased by the shrinking of the material of the handle upon cooling so that after the handle has cooled, the circuit closer is tightly gripped by the handle. As 5 shown in Fig. 2, the handle is shaped to conform with the outer surface of the circuit closer and is provided with a groove 10 which fits over the bead 3 and prevents sidewise displacement 10 of the handle relative to the circuit closer.

15 The circuit closer is mounted within a housing 11 of molded insulating material having side walls 12 in which are molded tubular inserts or binding posts 13. On the inner ends of these inserts are fixed contacts 14 having a plurality 20 of flexible contact arms 15. In the outer end of the inserts are threaded binding screws 16 which clamp the line conductors to the inserts. The circuit closer is assembled in the housing by sliding between the contacts 14. In this position the flexible contact fingers 15 frictionally 25 engage the outer surface of the terminals 1 and conduct electricity to the terminals. Since a plurality of spring contact fingers 15 are provided, the contact fingers align themselves with 30 the surfaces of the terminals and provide good electrical contact. It is also apparent that this construction permits rotation of the liquid contact switch about its axis. The wiping action 35 between the terminals and the contacts tends to prevent increased contact resistance.

At the bottom of the housing is a spring strip 17 provided with projections 18 which slidably 40 engage the periphery of the circuit closer at angularly spaced points and also having its ends 19 slidably carried in slots 20 in the bottom wall 45 of the housing. The projections 18 provide supports for the circuit closer and are also adapted to engage a notch 21 formed in the periphery of the glass bead 3, and thereby to hold the circuit closer resiliently in a fixed position. The circuit closer is held within the housing 11 and against the projections 18 by two curved spring strips 22 which engage the curved surfaces 23 of the handle on either side of the handle. As shown 50 in Fig. 2, the edges of the spring strips 22 engage the sides of the handle 6 and assist in centering the handle in the housing. The spring strips 22 are riveted to a support or mounting strap 24 which is secured to the top of the housing 11.

by screws 25 threaded into inserts 26. The mounting strap is adapted to be secured to an outlet box to mount the switch therein.

In the assembly of the switch, the handle 6 is secured to the liquid contact circuit closer and the contacts 14 are secured to the inner end of the inserts 13 in the side walls of the housing. The ends 19 of the spring strip 17 are then placed in the slots 20 in the bottom wall of the housing, 10 and the circuit closer is inserted in the housing so that the bottom of the glass bead 3 engages the projections 18 of the spring strip 17 and the terminals 1 engage the contacts 14. The mounting strap 24 is then secured to the top of 15 the housing by the screws 25, thereby holding the circuit closer in place.

In the use of the switch, the switch is mounted in an outlet box by means of the mounting strap 24. Due to the location of the opening 5 in the 20 diaphragm 2, the right-hand end of the mounting strap 24 should be at the top of the outlet box. When so mounted, vertical movement of the handle 6 causes the circuit closer to be rotated about its axis. When the handle is in the raised position, shown in full lines on Fig. 3, the opening 5 in the diaphragm 2 is submerged in the mercury, and an electric circuit is completed through the mercury between the terminals 1. When the handle is in the lowered position, as shown in dotted 25 lines in Fig. 3, the opening 5 is raised out of the mercury, and the circuit between the terminals 1 is broken. The handle is resiliently held in either the raised or the lowered positions by the engagement of one of the projections 18 with the 30 notch 21 in the bead 3. It is apparent that by changing the location of the opening 5 in the diaphragm 2, or by changing the positions of the notches 9 and 21, the switch can be adapted for mounting in other than vertical positions.

40 What I claim as new and desire to secure by Letters Patent of the United States is:

1. In an electric switch, a housing having spaced side walls, binding posts fixed in the housing side walls the outer ends being accessible for connection from the outside of the housing and the inner ends extending within the housing, opposed spring contacts carried by the inner ends of said binding posts, a liquid contact circuit closer between said contacts having an enclosure including opposed cup-shaped terminals, said terminals frictionally engaging said contacts whereby the terminals are rotatable on the contacts, and means supporting the circuit closer for rotation on said contacts.

55 2. In an electric switch, a cylindrical liquid contact circuit closer operable by rotation about its axis, a housing, spring means at the bottom of said housing, means secured to said housing and having a curved portion slidably engaging less than half of the periphery of said circuit closer for holding said circuit closer against said 60 spring means and providing a seat in which the circuit closer is rotatable, said spring means and said circuit closer being provided with interfitting portions whereby said circuit closer is resiliently held in a fixed position.

70 3. In an electric switch, a cylindrical liquid contact circuit closer operable by rotation about its axis, a curved member slidably engaging less than half of the periphery of the circuit closer on one side of its axis and providing a seat in which it is rotatable, and resilient means frictionally engaging the periphery of the circuit closer on the opposite side of its axis and on each side of an axis passing through the center of said curved

member, said circuit closer being held for rotation about its axis between said resilient means and said curved member.

4. In an electric switch, a cylindrical liquid contact circuit closer operable by rotation about its axis, a housing, a curved member slidably engaging less than half of the periphery of the circuit closer on one side of its axis and providing a seat in which it is rotatable, and a spring strip having an end slidable in said housing and having portions engaging the periphery of the circuit closer on the opposite side of its axis and on each side of an axis passing through the center of said curved member, said circuit closer being held for rotation about its axis between said spring strip 10 and said curved member.

5. In an electric switch, a cylindrical liquid contact circuit closer operable by rotation about its axis, a pair of supports slidably engaging the periphery of the circuit closer at angularly spaced 20 points on one side of its axis, and means holding said circuit closer against said supports for supporting said circuit closer for rotation about its axis, and means for rotating the circuit closer on said supports.

6. In an electric switch, a cylindrical liquid contact circuit closer operable by rotation about its axis, a spring strip having portions slidably engaging the periphery of said circuit closer on one side of its axis at angularly spaced points, means holding said circuit closer against said portions of the spring strip whereby said circuit closer is supported for rotation about its axis, and means for rotating the circuit closer about its axis.

7. In an electric switch, a cylindrical liquid contact circuit closer operable by rotation about its axis, a housing, a spring strip having an end slidably in said housing and having portions slidably engaging the periphery of said circuit closer on one side of its axis at angularly spaced points, and means holding said circuit closer against said spring strip whereby said circuit closer is supported for rotation about its axis, said spring strip and said circuit closer having detent portions whereby the circuit closer is resiliently held in position.

8. In an electric switch, a cylindrical liquid contact circuit closer operable by rotation about its axis, a housing for said circuit closer, a pair of spaced supports on the bottom of said housing slidably engaging the periphery of said circuit closer at angularly spaced points, and a strap secured to said housing and engaging the top of said circuit closer for holding said circuit closer against said supports whereby said circuit closer is supported for rotation about its axis.

9. In an electric switch, a cylindrical liquid contact circuit closer operable by rotation about its axis, said circuit closer including opposed cup-shaped terminals joined by a projecting bead of sealing material, means engaging said terminals for supporting the circuit closer for rotation, a notch in said bead, and spring means engaging said notch for resiliently holding the circuit closer 65 in a fixed position.

70 10. In an electric switch, a cylindrical liquid contact circuit closer operable by rotation about its axis, means for rotatably supporting the circuit closer including an arcuate seat slidably engaging less than half of the periphery of the circuit closer, resilient means for holding the circuit closer against said seat, and means for rotating the circuit closer on said seat.

11. In an electric switch, a cylindrical liquid

contact circuit closer operable by rotation about its axis, a pair of supports slidably engaging the periphery of the circuit closer at angularly spaced points on one side of its axis, and means including a curved seat engaging less than half of the periphery of the circuit closer on the opposite side of its axis whereby the circuit closer is supported for rotation between said supports and said seat.

12. In an electric switch, a cylindrical liquid contact circuit closer operable by rotation about its axis, a seat slidably engaging less than half of the periphery of the circuit closer on one side of its axis, and means holding the circuit closer against said seat whereby the circuit closer is supported for rotation.

ROBERT F. SAMBLESON.
